United States Patent Office

Des. 188,718
Patented Aug. 30, 1960

188,718

ELECTRIC VEHICLE

Frank J. Laher, 120 Camino Sohrante, Orinda, Calif.

Filed Sept. 2, 1958, Ser. No. 52,471

Term of patent 3½ years

(Cl. D14—3)

FIG. 1

FIG. 2

Figure 1 is a perspective view of an electric vehicle, showing my new design looking toward one side thereof; and

Figure 2 is another perspective view looking toward the front thereof.

The side not shown is like the side disclosed and the rear is conventional.

I claim:

The ornamental design for an electric vehicle, substantially as shown and described.
